CLAIM

The ornamental design for an artillery projectile extractor, as shown and described herein.

DESCRIPTION

The invention described and claimed herein may be manufactured, used, and licensed by or for the U.S. Government for U.S. Government purposes.

FIG. 1 is a perspective view of an artillery projectile extractor showing our new design;

FIG. 2 is a front view thereof;

FIG. 3 is a rear view thereof;

FIG. 4 is a first side elevation view thereof, wherein the view

180 degrees opposed thereto is a mirror image thereof; and,

FIG. 5 is a second side elevation view thereof, rotated 90

degrees from the view shown in FIG. 5, and wherein the view 180 degrees opposed to the view of FIG. 5 is a mirror image thereof.

For illustrative purposes only, FIGS. 1, 3, 4 and 5 show an elongated cylindrical handle, in broken lines, extending from the rear of the subject artillery projectile extractor; this handle forms no part of the claimed design. Further, the broken lines in FIG. 2 are included for the purpose of illustrating a portion of the artillery projectile extractor that forms no part of the claimed design.
